APPARATUS FOR THE PREPARATION AND MIXING OF FOUNDRY MOULDING MATERIALS

Erwin Knipp, Junkerath, and Karl Jellinghaus, Essen-Bredeney, Germany, assignors to Junkerather Gewerkschaft, Junkerath, Rhineland, Germany, a company of Germany, and A. Stotz A.-G. Eisengiesserei und Maschinenfabrik, Kornwestheim, Wurttemberg, Germany, a company of Germany

Application July 16, 1952, Serial No. 299,268

3 Claims. (Cl. 22—89)

The preparation of foundry moulding materials is generally effected in such manner that the sand used (old sand) is mixed with fresh sand after the coarser components have been sieved-off and the iron particles separated out, the mixture being subsequently treated in an edge mill or pan grinder. The object of the edge mill or pan grinder is to grind the fine clay-particles and mix them with the old and the fresh sand, so that a mass is formed which is substantially completely homogeneous.

The known methods operated with an edge mill or pan grinder are discontinuous operations, and not entirely satisfactory, because the finished sand in many cases still contains clay in the form of lumps.

The object of the invention is to provide apparatus by means of which the preparation of the sand is brought closer to perfection than was hitherto possible. The invention is not limited to moulding-sand, but it comprises also other moulding materials, particularly synthetic foundry moulding materials.

Apparatus according to the invention consists of a barrel or cylinder having an inlet for the moulding material and an outlet or discharge device at the end of the cylinder and also a centrifugal device, advantageously in the form of an impeller disposed within the cylinder and operating to fling the sand repeatedly against the inner wall of the cylinder from which it falls back. In addition, a guide plate is mounted in the cylinder which imparts an axial feed movement to the moulding material in its path from one centrifuging stage to the next in the cylinder.

Such apparatus operates satisfactorily in the preparation of moulding-sand.

When the requirements are more exacting, the apparatus may be combined with one or several rollers, which extend throughout the greater part of the cylinder and in the direction of the longitudinal axis of the cylinder, thus subjecting the material to additional pressure and kneading treatment, so that the crushing and distribution is considerably improved and so that the moulding sand will meet any requirements that may be made.

The cylinder is preferably so constructed as to rotate, the advantages being that the movement of the sand is aided, a unilateral wear of the cylinder is avoided, and any sand adhering to the inner walls of the cylinder can be removed by scrapers or the like.

The axial movement of the molding material through the cylinder can be effected by mounting the blades of the impeller at a slight inclination in the cylinder. In the path of the molding material stationary guide means are advantageously provided, which consist of inclined plates which impart an axial movement component to the flying sand passing it to the space between the pressure roller and the cylinder. The roller is provided to rotate above the lowermost position of the interior of the cylinder to leave a space between the roller and cylinder, so that the roller cannot become covered with sand and can operate smoothly. The roller may be mounted

so as to be deflectable or movable, preferably on a rocker arm, which is provided with reversing devices in the form of weights, springs or the like.

When, for working the material several times, several rollers are provided in series, they are so disposed that the roller-gaps decrease progressively in the direction of operation.

Two constructions of the apparatus according to the invention are diagrammatically illustrated by way of example in the accompanying drawings:

The more simple construction operating only with an impeller is shown in Figures 1 and 2, whereas the apparatus illustrated in Figures 3 to 5 comprises rollers as well as an impeller or centrifuge device.

15 In the drawings:

Figure 1 is a longitudinal section,

Figure 2 is a corresponding cross-section.

Fig. 2A is a sectional plan view taken on the line 2A of Fig. 1.

20 Figure 3 is a longitudinal section on the line III—III in Figure 4,

Figure 4 is a cross-section through the middle of the apparatus of Figure 3, and,

25 Figure 5 is a longitudinal section along the line V—V of Figure 4.

In the machine according to Figure 1, the sand—through the funnel 1—passes to the interior of the cylinder 2, which is mounted to be rotatable on the stationary rollers 4. The cylinder is rotated by a belt 5, which may be driven by an electric motor of any suitable design.

The ends of the cylinder are closed by stationary end-plates 6 and 7, which may be connected to the cylinder by means of anchor bolts 8. A centrifugal device is provided in the cylinder and consists of a shaft 10 on which are mounted blades 11. The shaft 10 extends through the end-plates 6 and 7 and is mounted in bearings in the stationary frame 14 at the positions 12 and 13. The shaft 10 is driven through a belt-pulley 15 and an appropriate transmission gear, by a separate motor, or by a drum motor.

35 Stationary guide means consisting of a plate 20 inclined from the vertical axis and a row of vertical guide plates 21, mounted on this plate in a position, inclined from the longitudinal axis, are also provided in the interior 40 of the cylinder.

45 When the moulding-sand enters the interior of the cylinder through the feed funnel 1 and through an opening provided in the end plate 6, it is caught by the blades 11 and flung with considerable force against the inner walls 50 of the cylinder 2, so that the clay-particles are battered, the various components of the sand or of any other foundry moulding material being at the same time intimately intermixed. The upwardly flung sand is fed over and over again to the centrifugal device (10, 11) by the 55 guide-means 20, 21, but each time at a different position, as the plates 21 guide the sand in the axial direction, so that it gradually reaches the left-hand end (in the drawing) of the cylinder 2, after having been repeatedly centrifuged, where it is finally discharged from the cylinder 60 by means of a guide-plate 25 or any other suitable discharging device.

The cylinder is provided with scrapers 26 or the like, which may be provided at different convenient positions on the periphery of the cylinder, and which are mounted 65 in known manner so as to be deflectable.

In the construction according to Figures 3 to 5, in addition to the parts above referred to, there are provided rollers 30, 31, and 32, by which the material, fed by the guide means 20, 21 and previously centrifuged, is subjected to further pressing and grinding, so that the nodules of clay in the fresh sand are substantially completely disintegrated, ground and distributed. In ordinary circum-

stances, the roller 30 will be sufficient. The cylinders 30 to 32 are not driven, being mounted in any appropriate manner for rotation in the frame, either in bearings, or, for example, in rocking levers 35 and 36.

The parts referred to with reference to Figures 1 and 2 of the drawings are shown in Figure 4, 33 being the motor for rotating the cylinder and the centrifugal means, the motor driving the shaft 41 through the belt-drive 40 and through the shaft 41 and the belt 5 driving the cylinder 2, and through the belt 42 the pulley 15—and thus the centrifugal shaft 10.

We claim:

1. Apparatus for the preparation and mixing of foundry moulding materials and the like comprising a base, a horizontal cylinder mounted on said base, means for rotating said cylinder about its horizontal axis at a relatively slow speed, inlet means on said base for delivering foundry moulding means into the one end of said cylinder, outlet means on said base for removing pulverized foundry moulding means from the opposite end of said cylinder, a rigid bladed centrifugal slinger mounted in said cylinder and extending the length thereof, said slinger having a horizontal axis parallel to and substantially below the axis of said cylinder, means for driving said slinger at a relatively high speed sufficient to impinge foundry moulding materials against the upper interior portion of said cylinder with a pulverizing force, a plurality of stationary guide plates mounted along a horizontal line within said cylinder above said slinger and in the path of materials being impinged against the cylinder wall by said slinger, each of said plates being positioned with its edge first engaging the slung material nearer the inlet end of the cylinder and its edge last engaging the slung material nearer the outlet end of said cylinder for moving the materials from the inlet end of the cylinder towards the outlet end, and a plurality of horizontal rollers in series within said cylinder between said guide plates and said slinger with gaps between the rollers and the inner periphery of the cylinders decreasing in size progressively in the direction of movement of the material.

2. Apparatus for the preparation and mixing of foundry moulding materials and the like comprising a base, a horizontal cylinder mounted on said base, means for rotating said cylinder about its horizontal axis at a relatively slow speed, inlet means on said base for delivering foundry moulding means into the one end of said cylinder, outlet means on said base for removing pulverized foundry moulding means from the opposite end of said cylinder, a centrifugal slinger mounted in said cylinder and extending the length thereof, said slinger having a horizontal axis parallel to and substantially below the axis of said cylinder, means for driving said slinger at a relatively high speed sufficient to impinge foundry moulding materials against the upper interior portion of said cylinder

der with a pulverizing force, a plurality of stationary guide plates mounted along a horizontal line within said cylinder above said slinger and in the path of materials being impinged against the cylinder wall by said slinger, each of said plates being positioned with its edge first engaging the slung material nearer the inlet end of the cylinder and its edge last engaging the slung material nearer the outlet end of said cylinder for moving the materials from the inlet end of the cylinder towards the outlet end, a horizontal pulverizing roll extending along the length of the inside of said cylinder between said guide plates and said slinger for crushing foundry moulding materials between its surface and the inside of the cylinder whereby foundry moulding materials are efficiently pulverized by the two repeated separate actions of impingement and crushing.

3. Apparatus for the preparation and mixing of foundry moulding materials and the like comprising a base, a horizontal cylinder mounted on said base, means for rotating said cylinder about its horizontal axis at a relatively slow speed, inlet means on said base for delivering foundry moulding means into one end of said cylinder, outlet means on said base for removing pulverized foundry moulding means from the opposite end of said cylinder, a centrifugal slinger mounted in said cylinder and extending the length thereof, said slinger having a horizontal axis parallel to and substantially below the axis of said cylinder, means for driving said slinger at a relatively high speed sufficient to impinge foundry moulding materials against the upper interior portion of said cylinder with a pulverizing force, and a plurality of stationary guide plates mounted along a horizontal line within said cylinder above said slinger and in the path of materials being impinged against the cylinder wall by said slinger, each of said plates being positioned with its edge first engaging the slung material nearer the inlet end of the cylinder and its edge last engaging the slung material nearer the outlet end of said cylinder for moving the materials from the inlet end of the cylinder towards the outlet end.
